United States Patent Office

Des. 197,259
Patented Dec. 31, 1963

197,259

BOAT

Claude E. Miller, Tulsa, Okla., assignor to
Dorothy M. Miller, Tulsa, Okla.

Filed Mar. 20, 1961, Ser. No. 64,387

Term of patent 14 years

(Cl. D71—1)

FIG. 1

FIG. 2

FIG. 3

FIG. 4

FIG. 5

FIGURE 1 is a side elevational view of a boat embodying my new design, the opposite side thereof being substantially the same in appearance;

FIGURE 2 is a top plan view thereof;

FIGURE 3 is a front view thereof;

FIGURE 4 is a rear view thereof;

FIGURE 5 is a fragmentary side cross-sectional view taken on the line 5—5 of FIGURE 2; and

FIGURE 6 is a front perspective view thereof.

The dominant features of my design reside in the portions shown in full lines.

What is claimed is:

The ornamental design for a boat, as shown and described.
